UNITED STATES PATENT OFFICE

127,517

DESIGN FOR A COMBINATION DOMESTIC WATER HEATER AND FOOD WARMER

Mary A. Fowler, Richmond, Va.

Application January 7, 1941, Serial No. 97,845

Term of patent 3½ years

To all whom it may concern:

Be it known that I, Mary A. Fowler, a citizen of the United States, residing at Richmond, in the county of Henrico and State of Virginia, have invented a new, original, and ornamental Design for a Combination Domestic Water Heater and Food Warmer, of which the following is a specification, reference being had to the accompanying drawing, forming part thereof.

I claim:

The ornamental design for a combination domestic water heater and food warmer, as shown.

MARY A. FOWLER.
